CLAIM

The ornamental design for a folding trolley, as shown and described.

DESCRIPTION

FIG. 1 is a front, left, and top perspective view of a folding trolley showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the folding trolley, shown in an alternate configuration of use, where the folding trolley is folded;

FIG. 9 is a front elevation view of the folding trolley as seen in FIG. 8; and,

FIG. 10 is a perspective view of the folding trolley, shown in an environment of use, where a box is placed on the folding trolley.

The broken lines in the drawings depict portions of the folding trolley that form no part of the claimed design.

(Continued)

Additional broken lines showing a box in FIG. 10 represent environmental structures and form no part of the claimed design.
